UNITED STATES PATENT OFFICE.

CLARENCE A. CARTER, OF KLEIN, MICHIGAN.

FENCE-POST.

No. 880,355.

Specification of Letters Patent.

Patented Feb. 25, 1908.

Application filed April 13, 1907. Serial No. 368,018.

To all whom it may concern:

Be it known that I, CLARENCE A. CARTER, a citizen of the United States, residing at Klein, in the county of Montmorency, State 5 of Michigan, have invented certain new and useful Improvements in Fence-Posts; and I do hereby declare the following to be a full, clear, and exact description of the invention, such as will enable others skilled in the art to 10 which it appertains to make and use the same:

The present invention relates to improvements in fence posts and has for its object to provide an exceedingly simple, inexpensive 15 and substantial device which may be easily set up at any desired point and which has such structure that the fence rails may be attached thereto without the use of bolts or similar fastening means.

20 The invention will be readily understood from an inspection of the annexed drawings, in which the same parts are designated by like numerals in the views and in which

Figure 1 is a perspective view of a fence 25 post embodying my improvement, and Fig. 2 is a detail view in front elevation of the upright member of the fence post.

Referring to the drawings, 5 designates the base member proper of the fence post, the 30 ends of which are beveled or rounded, as at 6, to provide an attaching surface for the side members of the fence post, as hereinafter described.

Attached to the upper surface of the base 5 intermediate the ends thereof is an upright 7, the top of which is formed with the oppositely beveled surfaces 8. The upright 7 is provided at its opposite sides with a series of cut-away portions 9 in the manner of bayonet 40 slots and which are adapted to receive and support the ends of the rails 10 of the fence. The fence post is also provided with side-pieces 11, 11, attached respectively to the beveled ends 6 of the base and the beveled 45 surfaces 8 of the upright 7 by bolts, nails or other preferred means.

As will be seen from Fig. 2, the cutaway portions 9 of upright 7 are formed in alining pairs, but it will be understood that said cut-away portions instead of alining may be located in staggered relation. Owing to the formation of said portions as bayonet slots, the rails 10 will be firmly retained in place in the lower portion of said slots and will be prevented from accidental displacement. The 50 rails may be bolted or nailed to the uprights if desired, although this is unnecessary owing to the bayonet slot construction of the cut-away portions.

It will be apparent from the drawings that 60 the entire fence post is in the form of a triangle, the base of which is the base member 5 of the post, and that owing to this construction the middle post or upright 7 will be in a measure protected from rain and less liable 65 to rot therefrom.

The various sections of the fence posts may be manufactured separately and when packed for transportation or storage, occupy but little space and can be readily and quickly put 70 together and moved from one position or location to another.

What is claimed, is—

A triangular fence post, composed of a base portion, inclined sides attached to the ends 75 thereof, and an upright attached to said base portion intermediate the ends thereof, said upright being provided at its upper end with oppositely-beveled surfaces forming attaching faces for said inclined sides, the opposite 80 edges of said upright having a series of bayonet slots formed therein and adapted to receive the rails.

In testimony whereof, I affix my signature, in presence of two witnesses.

CLARENCE A. CARTER.
